(57) CLAIM

The ornamental design for a table and stools for swimming pool, as shown and described.

DESCRIPTION

FIG. 1 is a perspective view of a table and stools for swimming pool, with the wall of swimming pool and of an umbrella which may optionally be connected to the apparatus of the design (which are both not part of the design) both shown in phantom outline;

FIG. 2 is a view similar to FIG. 1, with the phantom lining removed;

FIG. 3 is a top plan view of the table and stools shown in FIG. 2;

FIG. 4 is a front side elevational view of the table and stools of FIG. 3;

FIG. 5 is a back side elevational view of the table and stools of FIG. 3;

FIG. 6 is a right side elevational view of the table and stools of FIG. 3;

FIG. 7 is bottom plan view of the table and stools of FIG. 3; and,

FIG. 8 is a left side elevational view of the table and stools of FIG. 3 embodying my design.
